UNITED STATES PATENT OFFICE.

RICHARD LAWA, OF NEW YORK, N. Y.

COMBINATION GAS-RANGE.

1,340,615.

Specification of Letters Patent. Patented May 18, 1920.

Application filed July 12, 1919. Serial No. 310,451.

To all whom it may concern:

Be it known that I, RICHARD LAWA, a citizen of Czecho-Slovakia, and a resident of New York city, in the county of Bronx 5 and State of New York, have invented new and useful Improvements in Combination Gas-Ranges, of which the following is a specification.

My invention relates to improvements in 10 combination gas ranges for kitchens and like places, and it consists in the combinations, arrangements, and constructions herein described and claimed.

An object of my invention is to provide 15 a combination gas range, so constructed and arranged that it may be quickly converted into a work-table, and in which provision is made for the employment of a variety of devices, designed to be used in cooking operations, and interchangeable in positions, 20 in order that a variety of cooking operations may be performed in a relatively small space.

My invention has for a further object the 25 provision of a device of the above character which is simple as well as strong and durable in construction, may be manufactured at small cost and is highly convenient and serviceable in practical use.

30 One of the many possible embodiments of the invention is illustrated in the accompanying drawings forming part of this application, and in which:—

Figure 1 is a view in perspective of a 35 range made in accordance with my invention, parts of the structure being shown in broken lines.

Fig. 2 is a cross-section, taken on the line 2—2 of Fig. 1.

40 Fig. 3 is a perspective view of the structure as it appears when converted into a work-table.

Fig. 4 is a view in front elevation of the 45 structure shown in Fig. 1, all the parts being, however, in full lines.

Fig. 5 is a cross-section, taken on the line 5—5 of Fig. 3.

Fig. 6 is a top plan view with parts in section.

50 Fig. 7 is a perspective view, partly in section, showing a method of arranging various parts.

Fig. 8 is a cross-section, taken on the line 8—8 of Fig. 7.

55 In the present embodiment of the invention, I employ a rectangular frame, made

preferably of iron and in one piece, and consisting of the side plates 10 11 and the end plates 12 13, as best shown in Fig. 6. With this frame is cast all around or otherwise provided, a short distance below its top edge, an inwardly projecting ledge 14. With each of the end plates, a distance below the ledge 14, there is also cast a second ledge 15. Secured upon the end plate 65 ledges 15 and connecting the same, are the spaced-apart parallel rails 16, upon which are secured the gas burners, herein shown to consist of circular burners 17, alined by pairs transversely of the frame, and of a 70 longitudinal burner 18 also disposed transversely.

The rear plate 11 and the end plates 12 13 are made of greater depth than the front plate 10; and the said end plates are cast 75 with inwardly projecting bottom ledges 19, for the reception and support of a work plate 20, whose dimensions are such as to permit it to be placed on the ledge 14 within the frame (Fig. 3), when it is desired 80 to convert the range into a work-table. When it is desired to use the range for cooking purposes, as will be presently described, the work plate 20 is removed from the ledge 14 and stowed away on the ledges 85 19; it being observed that the parts are so arranged that the ledge 14 supports the plate over the burners, while the ledges 19 support the same under the burners.

The frame so constructed is supported 90 upon legs as 21, of which there are four in number, one secured to the frame under each corner thereof. For purposes of simplicity and stability, these legs are preferably made of angle-iron, and they are connected and 95 braced by the longitudinal and transverse rails 22 and 23, also made of angle-iron and on which is disposed a shelf 24 for the convenient support of cooking utensils, when not in use.

Attached to and projecting forwardly 100 from the end plates are brackets 25, designed to support a gas pipe 26, which may be connected with a suitable source of gas supply. Leading from the pipe 26 are 105 branch pipes 27, which connect with the burners—one pipe for each burner. Associated with each branch pipe is a valve 28 through which the flow of gas is controlled.

As best shown in Fig. 1, I provide for 110 the support of cooking utensils, a grate 29, adapted to be set upon the ledge 14 within

the frame, the same being of a very simple and inexpensive construction, consisting of spacedly connected parallel bars 30, which extend transversely of the frame. This 5 grate is preferably designed to occupy only one-half the space within the frame, the remainder of the space being divided between the baking plates 31 and 32, which also rest upon the ledge 14. These plates are 10 designed to be used as griddles, on which to bake the so-called butter cakes, wheat cakes and the like. They may also be employed as a support for a heat conserving pan 33; and to this end they are provided with a 15 plurality of apertures to permit the heat to rise in columns uninterruptedly therethrough. Thus the plate 31, which comes substantially over the longitudinal burner 12, is preferably provided with elongated 20 apertures 34, while the plate 32 is provided with circular apertures 35.

The heat conserving pan 33 has its base portion 36 divided into two longitudinal compartments (not shown), designed to 25 receive food which is to be cooked, or which, when cooked, is to be kept in a warm state until served. Rising from the base and inclosing the compartments are the arcuate casings or tops 37 38, each similarly made 30 of two parts 39 and 40, of which the parts 39 are permanently secured to the base, while the parts 40 are pivoted to the parts 39 as at 41 on the outer and opposite sides thereof. The parts 40 are made large 35 enough to telescope the parts 39 when moved rearwardly about their pivots. Access may be had, therefore, to either compartment without opening the other one.

As best illustrated in Fig. 7, I also provide 40 a pan 42, open at its top and designed to be placed on the grate 29 and to contain water, in which may be set any suitable receptacles as 43 containing food to be cooked or kept warm.

45 To the outer rear ends of the end plates 12 and 13 are secured the uprights 44 and

45, respectively, formed with forwardly enlarged top ends for the suitable support of a shelf 46, on which may be placed the pans not in use.

From the foregoing description, taken in connection with the accompanying drawings, it will be understood that the grate 29, plates 31 and 32, and pans 33 and 42 are all 50 readily removable, and, if desired, are interchangeable in a variety of ways with respect to position, as best befits the requirements of the cook. The shelves 24 and 46 afford convenient places on which to place these parts, when removed. Moreover, the 55 structure may be quickly converted into a worktable by placing the work plate 20 upon the ledge 14. In homes and restaurants having small kitchens, where the cooks have only a limited space within which to 60 work, the advantages of my improved range 65 will be apparent.

Having thus described my invention, what I claim is:—

In a gas range, the combination of a leg 70 supported rectangular frame consisting of front and rear side plates and connecting end plates, the front side plate being of less depth than the other plates, the end plates being formed with inwardly projecting 75 ledges in a plane below the front side plate, an inwardly projecting upper ledge formed on the frame all around just below its top edge, ledges and connecting rails carried by the frame in a plane between said end ledges 80 and said upper ledge, gas burners disposed on said connections, a table-board engageable either with said end plate ledges below the burners or with said upper ledges over the burners, and devices by means of which 85 cooking operations may be effected engageable upon the upper ledge and interchangeable as to position.

In testimony whereof I have signed my name to this specification.

RICHARD LAWA.
